Richard L. Huggins, Lima, N.Y., assignor to Bausch & Lomb Incorporated, Rochester, N.Y., a corporation of New York

Filed Dec. 5, 1968, Ser. No. 14,812

Term of patent 14 years

Int. Cl. D16—08

U.S. Cl. D57—1

FIG. 1

FIG. 2

FIG. 3

FIG. 1 is a front view of a pair of sunglasses showing my new design;

FIG. 2 is a side view of said pair of sunglasses taken from the right side thereof as viewed in FIG. 1; and

FIG. 3 is a top plan view thereof.

The side not shown has substantially the same appearance as the side shown.

The temples are shown broken away in FIG. 3 for convenience of illustration.

The dominant features of my design reside in those portions shown in solid lines.

I claim:

The ornamental design for a pair of sunglasses, substantially as shown and described.
